(57) **CLAIM**

The ornamental design for a device connection cable, as shown and described.

DESCRIPTION

FIG. 1 is a front perspective view of a device connection cable according to a first embodiment of our design;

FIG. 2 is a front elevation view of the device connection cable of FIG. 1;

FIG. 3 is a back elevation view of the device connection cable of FIG. 1;

FIG. 4 is a right elevation view of the device connection cable of FIG. 1;

FIG. 5 is a left elevation view of the device connection cable of FIG. 1;

FIG. 6 is a top elevation view of the device connection cable of FIG. 1;

FIG. 7 is a bottom elevation view of the device connection cable of FIG. 1;

FIG. 8 is a front perspective view of a device connection cable according to a second embodiment of our design;

FIG. 9 is a back elevation view of the device connection cable of FIG. 8;

FIG. 10 is a front elevation view of the device connection cable of FIG. 8;

FIG. 11 is a right elevation view of the device connection cable of FIG. 8;

FIG. 12 is a left elevation view of the device connection cable of FIG. 8;

FIG. 13 is a top elevation view of the device connection cable of FIG. 8; and,

FIG. 14 is a bottom elevation view of the device connection cable of FIG. 8.

In the drawings, the broken lines depict unclaimed subject matter. The jagged broken lines depict the boundaries of the claim and form no part thereof.

1 Claim, 5 Drawing Sheets
